UNITED STATES PATENT OFFICE.

HENRY V. WILLE, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

WASHOUT-PLUG.

1,219,206.

Specification of Letters Patent. Patented Mar. 13, 1917.

Application filed December 15, 1916. Serial No. 137,204.

To all whom it may concern:

Be it known that I, HENRY V. WILLE, a citizen of the United States, residing in Philadelphia, Pennsylvania, have invented 5 certain Improvements in Washout-Plugs, of which the following is a specification.

My invention relates to certain improvements in screw plugs, especially those used for boilers, of the locomotive, marine, or 10 stationary type.

One object of my invention is to improve the construction of the plug and to reduce the cost of manufacture.

A still further object of the invention is 15 to make the plug so that it will not leak.

Heretofore, these plugs have been made from cast brass, and, the casting being porous, there was a certain amount of leakage.

In the accompanying drawings: 20

Figure 1 is a side view of a washout plug illustrating my invention;

Fig. 2 is a plan view;

Fig. 3 is a sectional plan view on the line 3—3, Fig. 1;

Fig. 4 is a detached perspective view of the center section of the plug;

Fig. 5 is a perspective view of the cupped blank forming the outer section of the plug;

Figs. 6, 7 and 8 are sectional views showing different steps in the process of manufacture; and

Fig. 9 is a view of a modification.

Referring to the drawings, 1 is a center made of steel, or other suitable material, 35 having, in the present instance, a hexagonal, square, or other shaped, body portion 2, and a hexagonal, square, or other shaped, extension 3 to which can be applied any suitable wrench.

40 4 is a cup-shaped outer section of the plug made from a sheet of rolled brass pressed into shape, as clearly shown in Fig. 5.

The steel center is placed within the cup-shaped section 4, as shown in Fig. 6, and 45 the two sections are then forced through a die, which will cause the inner surface of the cup-shaped section to conform to the hexagonal, or other shaped, body portion of the center 1.

50 The cup is of a greater length than the body portion and extends beyond the body portion, when the parts are assembled, as shown in Fig. 6, and will be turned over the upper edge of the said body portion, as shown in Fig. 7, so that

the cup-shaped section 4 is held from moving longitudinally on the center and as it is shaped to correspond to the irregular shape of the body portion of the plug it will turn with the center. The thread is cut on the periphery of the cup-shaped section 4, as shown in Fig. 8, making the finished plug illustrated in Fig. 1, so that, when the plug is screwed into the threaded opening, the cup-shaped section must turn with the center 1.

In Fig. 6, I have shown a hexagonal center, while, in Fig. 9, I have shown a square center. In some instances the body portion of the center may be hexagonal, or other shape, and the extension may be square.

In Fig. 9, I have illustrated the center 1^a as having an annular groove therein and the metal of the cup-shaped section 4^a is driven into this groove, when the plug is passed through a die, holding the outer section firmly to the center.

By forming the cup-shaped section from a pressed rolled plate of brass, I am enabled to make the plug, non-porous, as the rolling of the sheet of brass closes the pores. Furthermore, by using a steel center, and a comparatively thin shell of brass, I materially reduce the cost of manufacture.

I claim:

1. The combination in a washout plug, 85 of a center and an outer section secured to the center, said outer section being made of rolled sheet metal so that the plug will be non-porous.

2. The combination in a washout plug, of 90 a steel center provided with an irregularly shaped body portion; and an outer section made from sheet brass pressed into shape and surrounding the body portion and threaded at its periphery.

3. A washout plug made in two sections, the inner section having an irregular body portion and an irregular extension less in diameter than the body portion; and a cup-shaped outer section made from sheet brass 100 and having its edge turned over the body portion and threaded on its periphery so that the outer section must turn with the body portion.

4. The process herein described of making a washout plug, said process consisting in making an irregularly shaped center, and a cup-shaped outer section from rolled brass,

then assembling the two sections and passing them between dies so as to cause the outer section to conform to the shape of the center.

5. The process herein described of making a washout plug, said process consisting in forming a center having a body portion of irregular shape and a reduced extension and making a cup-shaped outer section from

rolled brass, then assembling the two sections and passing them through dies so that the cup-shaped section will conform to the shape of the body portion and will extend over the shoulder formed by the reduction of the center, preventing the withdrawal of 15 the center from the outer section.

HENRY V. WILLE.
